(57) **CLAIM**

The ornamental design for an inverted French F-channel, as shown and described.

DESCRIPTION

FIG. 1 is front view of an inverted French F-channel, which shows my new design, with the rear view being in essence a mirror image of the front, and with the set of roller bearings, inverted U-channel, and load-bearing surface shown in broken lines being for illustrative purposes only and forming no part of my design;

FIG. 2 is a perspective view thereof, with the set of roller bearings and rectangular channel stop shown in broken lines being for illustrative purposes only and forming no part of my design, and with the channel being shown broken in the middle, in this and in the following figures, to show indeterminate length;

FIG. 3 is a top view thereof;

FIG. 4 is a bottom view thereof;

FIG. 5 is a first side view thereof; and,

FIG. 6 is a second side view opposite the first side thereof.
